UNITED STATES PATENT OFFICE

VICTOR O. STROBEL, OF PHILADELPHIA, PENNSYLVANIA.

HOT-BLAST STOVE.

SPECIFICATION forming part of Letters Patent No. 414,734, dated November 12, 1889.

Application filed September 11, 1889. Serial No. 323,610. (No model.)

To all whom it may concern:

Be it known that I, VICTOR O. STROBEL, of Philadelphia, Philadelphia county, Pennsylvania, have invented certain new and useful 5 Improvements in Hot-Blast Stoves, of which the following is a specification.

This invention pertains to improvements in regenerative hot-blast stoves designed for use in the heating of air, gas, &c.

10 My improvements will be readily understood from the following description, taken in connection with the accompanying drawings, in which—

Figure 1 is a vertical section of a hot-blast 15 stove embodying my improvements, the plane of the section being indicated by dotted line *b* of other figures; Fig. 2, a similar section in the plane of line *a*; Fig. 3, a horizontal section in the plane of line *c*, and Fig. 4 a horizontal section in the plane of line *d*.

In the drawings, *A* indicates the usual inclosing metallic shell; *B*, the lining-wall thereof; *C*, the brick floor of the stove; *D*, a circular combustion-chamber wall concentrically 25 disposed and extending from the floor of the stove to near the roof thereof; *E*, four radial walls extending from the combustion-chamber wall to the shell-wall and from the floor to the roof of the stove and forming four seg-

30 mental regenerator-chambers exterior to the combustion-chamber; *F*, a cylindrical lining at the base of the combustion-chamber, this lining forming what may be called the "firepot" of the combustion-chamber; *G*, the combustion-chamber formed by the wall *D*, this chamber extending from the floor of the stove upward to near the roof of the stove; *H*, a pipe-connection from the exterior of the stove to the base of the combustion-chamber to 35

40 serve as a gas-inlet; *J*, a second similar connection to serve as a hot-blast outlet; *K*, openings through the bases of the radial walls *E*, whereby the entire base of the stove around the combustion-chamber forms a series of 45 chambers in free communication with each other; *L*, the arched roof of the combustion-chamber; *M*, regenerator-work arranged in two of the regenerator-chambers, this regenerator-work extending from near the 50 base of the stove to near the roof thereof; *N*, a pipe-connection at the top of the stove,

placing the exterior of the stove in communication with the two regenerator-passes *M*, this pipe-connection being designed to serve in common for the outlet of gas to the chimney 55 and for the inlet for cold blast; *O*, the passage between the roof of the stove and the roof of the combustion-chamber, serving to place the two regenerator-passes *M* in communication with each other and with the pipe-connection *N*; *P*, regenerator-work arranged within the two chambers intermediate of the chambers *M*, this regenerator-work extending vertically, like the regenerator-work *M*—that is to say, from near the base of the stove to 60 near the roof thereof; *R*, Fig. 4, radial walls arranged in the base of the stove exterior to the combustion-chamber and extending from the floor of the stove to the base of the regenerators, these walls serving to aid in supporting the regenerator-work, the walls being either solid or provided with openings like *K*, as desired; and *S*, openings at the ends of the arch *L*, extending vertically from the top of the regenerators *P* to the arch *L* and having a width equal to that of the combustion-chamber, these openings placing the tops of the regenerator-passes *P* in free communication with each other and with the combustion-chamber. 70

The pipe-connection *H* should have the usual gas-valve; the pipe-connection *J* should have the usual hot-blast valve, and the pipe-connection *N* should have the usual chimney-valve in one of its branches and the usual cold-blast valve in the other of its branches. The pipe-connection *H* may, if desired, be branched to serve as gas-inlet and hot-blast outlet, as is the common practice, and in such case the pipe-connection *J* may be dispensed 85 with.

Assume the stove to be cold. The cold-blast inlet valve and the hot-blast-outlet valve are to be closed. The chimney-valve and the gas-valve are to be opened. Gas, along with air 95 of combustion properly supplied, now enters the pipe-connection *H* and goes into combustion in the combustion-chamber. The products of combustion go to the top of the combustion-chamber, then pass horizontally both 100 ways through the openings *S* to the top of the regenerators *P*, then pass down the re-

generator-passes P to the base of the stove, then pass horizontally through the openings K to the bases of the regenerator-passes M, then pass up the regenerator-passes M to the top of the stove, and then pass convergently therefrom through the passage O to the pipe-connection N, through which they pass to the chimney. During the process the regenerator-work becomes heated. When the stove is sufficiently heated, then the gas is shut off and the chimney-valve is closed. The hot-blast valve and cold-blast valve are now to be opened. The cold blast enters the top of the stove at the pipe-connection N, and the current divides in the passage O and goes down the regenerator-passes M to the base of the stove, where it passes through the openings K and goes up the regenerator-passes P to the top of the stove, where the two currents rising through these two regenerator-passes join and move down the combustion-chamber and out at the hot-blast pipe-connection, the blast in its passage through the stove absorbing heat from the regenerator-work. When necessary, the stove is again put under blast, it being understood, of course, that the stoves are to be worked in multiple, as usual.

Cleaning-openings may be provided where desired.

30 I claim as my invention—

1. In a hot-blast stove, the combination, substantially as set forth, of a vertically-disposed metallic shell, a lining-wall therefor, a pipe-connection at the top of the stove for chimney-gases and cold-blast, a centrally-disposed vertical combustion-chamber, a pipe-connection at the base of the combustion-chamber for gas and hot blast, vertical walls extending radially

from the combustion-chamber to the lining-wall of the stove, a pass of regenerator-work on each opposite side of the combustion-chamber and communicating with the top thereof, and a pass of regenerator-work on each opposite side of the combustion-chamber intermediate of the first-mentioned passes and communicating with each other and said top pipe-connection at the top of the stove and with said first-mentioned passes at the base of the stove.

2. In a vertical hot-blast stove, the combination, substantially as set forth, of a circular wall concentric with the stove-circle, roof-arch L over the same and below the roof of the stove, pipe-connections N at the top of the stove, radial walls E, regenerator-passes P, communicating at the top with the combustion-chamber, regenerator-passes M, communicating at the bottom with said passes P and at the top with said pipe-connection, and pipe-connections at the base of the combustion-chamber.

3. In a hot-blast stove, the combination, substantially as set forth, of a central combustion-chamber, pipe-connections at the base thereof, a pipe-connection at the top of the stove, and a circumferential series of regenerator-passes around the combustion-chamber, the alternate ones of said passes communicating at the top with the combustion-chamber, and the intermediate ones of said passes communicating at their bases with the bases of said alternate passes and at their tops with said top pipe-connection.

60 VICTOR O. STROBEL.
